US00D969155S

(12) **United States Design Patent** (10) Patent No.: **US D969,155 S**
(45) Date of Patent: **** Nov. 8, 2022**

(54) **DISPLAY SCREEN OR PORTION THEREOF
WITH GRAPHICAL USER INTERFACE**

(71) Applicant: **BioReference Health, LLC**, Elmwood Park, NJ (US)

(72) Inventors: **Richard Charles Schwabacher, II**, Elmwood Park, NJ (US); **Vincent Pacione**, Elmwood Park, NJ (US); **Ryan Wiaranowski**, Elmwood Park, NJ (US); **Alexa Katz**, Elmwood Park, NJ (US); **Daniel Nosonowitz**, New York, NY (US); **Jin Sang Yoon**, New York, NY (US); **Riley Walker**, New York, NY (US); **Xuecheng Xu**, New York, NY (US)

(73) Assignee: **BioReference Health, LLC**, Elmwood Park, NJ (US)

(**) Term: **15 Years**

(21) Appl. No.: **29/840,398**

(22) Filed: **May 27, 2022**

Related U.S. Application Data

(63) Continuation of application No. 29/812,573, filed on Oct. 22, 2021, now Pat. No. Des. 953,371.

(57) **CLAIM**

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

The FIGURE is a front view of a display screen or portion thereof with graphical user interface showing the claimed design.

The broken lines in the FIGURE show a display screen or portion thereof, and form no part of the claimed design.
